UNITED STATES PATENT OFFICE.

VINCENT CRANE RICHMOND, OF HARROW-ON-THE-HILL, AND GEORGE HERBERT SCOTT,
OF PURLEY, ENGLAND.

CONSTRUCTION OF RIGID AIRSHIPS.

Application filed October 23, 1924, Serial No. 745,462, and in Great Britain October 30, 1923.

This invention relates to the construction of rigid airships the hull structure of which comprises transverse frames and peripheral longitudinal girders, and has for its primary object to obviate any lateral load on the longitudinal girders consequent upon the transmission of the lift of the gasbags to the hull of the airship. This is effected according to the present invention by an arrangement of enveloping wiring for the gasbags which transfers all load due to gas pressure from the longitudinal girders to the transverse frames, the diagonally arranged wires of the enveloping system being attached to the transverse girders only, either directly or through interposed linkage, and not to any longitudinal member.

The surface which includes the diagonally strung wires between adjacent transverse frames may be given a regular or more or less regular shape; for example, with two sets of parallel wires diagonally stretched between two transverse frames at the same angle on either side with respect to the longitudinal axis, the surface containing the wires prior to distortion by gas pressure would be a hyperboloid of revolution, and by varying the angular relation between wires and transverse frames or the initial tension or slackness of the wires, the curvature of the resulting containing surface can be varied substantially as may be found desirable so that, for example, the curvature of the surface may be arranged to be a maximum at the top of the ship where the pressure is greatest, and a minimum at the bottom. Similarly the spacing of the wires and/or their gauge may be varied in any desirable manner, as for example by increasing the distance between successive wires from the top point of the frames downward.

The invention is illustrated in the accompanying drawings, wherein Fig. 1 is a diagrammatic transverse section of a rigid airship; Fig. 2 is a perspective view of a section or bay of same; and Fig. 3 a developed side elevation of same.

In these diagrammatic drawings A, A represent two adjacent main transverse frames; B the main longitudinal girders and B' the auxiliary longitudinal girders as in the usual construction of rigid airships. The wires of the enveloping system of the gasbag are denoted generally by C, and these wires ex-

tend diagonally between the two main transverse frames A, A, being connected at their ends either directly with the said transverse frames, or with catenaries D or linking wires or bridles which, as shown in the drawings, are connected with the main transverse frames A between successive main longitudinal girders B. The result of this construction is that the enveloping wires C lie in an outwardly concave curved surface, the curvature of which may be varied as desired, as above explained, and the production and presence of this inward bulge in the enveloping wires is an essential feature of this invention.

In the construction shown in the drawings the inclination of the enveloping wires at the top part of one section or bay is such that a wire, which is attached to one of the transverse frames at a point thereon corresponding with the intersection of a given longitudinal girder, is attached at its other end to an adjacent main transverse frame at a point displaced circumferentially to an extent approximately equal to the distance between successive main longitudinal girders, whereas at the bottom part the inclination of the enveloping wires is approximately such that the displacement of one end of the wire with respect to the other is more like twice the distance between successive main longitudinal girders.

In addition to removing lateral load due to the gasbag lift from the longitudinals, this construction lends itself to the gasbag loads being transferred to points more or less low down on the transverse frames, according to the inclination of the wires.

Having thus described the nature of the said invention and the best means we know of carrying the same into practical effect, we claim:

1. In a rigid airship embodying transverse ring-shaped girders, longitudinal members and gasbags, enveloping wiring for the gasbags comprising wires stretched between adjacent transverse girders and extending diagonally with respect to and free of the longitudinal members, said wires forming inwardly bulging cages for the gasbags.

2. In a rigid airship according to claim 1, means for connecting the diagonal wires to the transverse girders comprising catenaries or linkage wires or bridles looped between

a series of points around the transverse girders and to which the ends of said diagonal wires are connected.

3. In the construction of rigid airships embodying transverse ring-shaped girders, longitudinal members and gasbags, enveloping wiring forming inwardly bulging cages for the gasbags and comprising two series of mutually inclined diagonally arranged wires extending between adjacent pairs of main transverse frames and passing within the longitudinal members without contact therewith at intermediate points thereof between adjacent transverse frames.
- 10 4. In the construction of rigid airships embodying transverse girders, longitudinal

members and gasbags, enveloping wiring forming inwardly bulging cages for the gasbags and comprising two series of mutually inclined diagonally arranged wires extending between adjacent pairs of main transverse frames and passing within the longitudinal members without contact therewith at intermediate points thereof between adjacent transverse frames, said diagonally arranged wires being connected to bridles attached in a series around the main transverse frames.

20 In testimony whereof we have signed our names to this specification.

VINCENT CRANE RICHMOND.
GEORGE HERBERT SCOTT.
